E. FRIEDRICH

SHOW CASE AND FREEZER COUNTER TOP

Filed June 6, 1924

INVENTOR

Edward Friedrich.

BY
Albert E. Dietrich
ATTORNEY

UNITED STATES PATENT OFFICE.

EDWARD FRIEDRICH, OF SAN ANTONIO, TEXAS.

SHOW-CASE AND FREEZER-COUNTER TOP.

Application filed June 6, 1924. Serial No. 718,380.

To all whom it may concern:

Be it known that I, EDWARD FRIEDRICH, a citizen of the United States, residing at San Antonio, in the county of Bexar and 5 State of Texas, have invented certain new and useful Improvements in Show-Case and Freezer-Counter Tops, of which the following is a specification.

My invention is an improved display top 10 for show cases, freezer counters and the like and it has for its objects to provide a new and useful means for holding the top glass or bunker top in place without danger of chipping the same or of the same becoming 15 loose.

Heretofore it has been a common practice to fasten the top plates with dowels inlaid and in the event of replacement, new top plates would not fit in correct position; my 20 invention has for another object to overcome this objectionable feature.

A further object of the invention is to provide a display top for counters of various kinds, in which the glass projects beyond 25 the counter's frame and is concealed on the edge by a moulding that prevents chipping of the edges of the glass, the moulding being spaced from the top frame wall to leave a space between the same 30 through which dirt and water which might work through between the glass and moulding may pass and fall on the floor clear of the case, thereby not coming in contact with the felt under the glass as is the case in those 35 tops now commonly employed having rabbet joints.

Again it is an object of my invention to provide an improved joint between the vitreous sections of the top by the use of a 40 rubber gasket and cement which secures the joint for expansion and contraction, and is at the same time waterproof.

With other objects in view which will be apparent to those skilled in the art the invention 45 also resides in those novel details of construction, combination and arrangement of parts, all of which will be first fully described, then be specifically pointed out in the ap-

pended claims, reference being had to the accompanying drawings, in which:

Figure 1 is a perspective view of a show case top embodying my invention.

Figure 2 is a vertical longitudinal section on the line 2—2 of Figure 1.

Figure 3 is an inverted plan view of the 55 same.

Figure 4 is an enlarged detail section on the line 4—4 of Figure 3.

Figure 5 is an enlarged detail section on the line 5—5 of Figure 3.

In the drawings, in which like numerals of reference designate like parts in all the figures, 1 represents the main frame of the top which is of general outline to fit the particular cabinet desired (usually rectangular outline), the frame having a flange or head portion 2 to over-lie the side of the counter or case 3 (see dotted lines in Figure 4) on which it is placed.

When the vitreous top plate is made of a 70 plurality of parts the frame 1 is provided with one or more cross members 4 to overlie the joint or joints between the sections. The frame 1 is covered with felt 5, or other suitable sound deadening material, and it 75 is on this that the vitreous top plate is laid. This top plate may consist of a single glass plate 6 or it may be composed of a number of plates 6 and 7, either or all of which may be transparent or opaque as desired and they 80 may be of different thicknesses if desired.

In the drawings I have shown, for purposes of illustration, the top as having a top plate composed of a transparent section 6 and an opaque section 7, the former being 85 glass and the latter being opaque vitreous material and of a greater thickness than the former. The opposing edges of the plate sections 6 and 7 are spaced a short distance apart and this space is filled with a rubber 90 gasket 9 that is cemented at 10—10 to the plate sections 6 and 7 respectively by any suitable cement. The opposing edges of the plate sections 6 and 7, as before intimated, lie over the cross bar 4 of the frame 1 and 95 are supported thereby.

The combined area of the vitreous top plates is in excess of the area of the top frame 1 so that the outer edges of the top plates project beyond the outer edges of the frame 1 and leave a space 11 between the frame 1 and the moulding 12 which surrounds the frame 1 and the outer edge of the top plate and is held in pressure contact with the outer edge of the top plate by 5 suitable screws 13 that pass through the moulding into the frame 1, suitable rings or washers 14 being carried by the screws in the space 11 as best shown in Figure 4.

From the foregoing description, taken in connection with the accompanying drawings, it will be observed that in order to replace the top plates 6, 7, it is only necessary to loosen the several screws 13 and lift the plate off. Then after replacing the same 20 the screws may be tightened and the moulding 12 may again be clamped to the edge of the plate and thereby hold the plate tightly in position on the frame 1.

It will also be observed that by reason of 25 the overhang of the plates and the provision of the space 11 surrounding the frame 1 any dust or water that may work between the edge of the top plates 6 and 7 and the moulding 12 and pass through the space 11 and 30 drop on the floor and will not work into contact with the felt 5.

Furthermore by providing the rubber gasket 9 cemented to the opposing edges of the plate sections 6 and 7 dirt and water will 35 not pass therebetween and expansion and contraction will be compensated for in this joint.

The whole top then, it will be seen, is 40 waterproof and can be used without fear of the moisture passing through and into the interior of the cabinet 3.

While I have shown the top as having a plurality of plate sections 6 and 7 it is obvious that the number of sections from one 45 up will depend upon the size of the top and the nature of the cabinet over which it is to be placed, and I do not wish to be restricted in this application to any particular number of plate sections.

50 What I claim is:

1. In counters and show cases, a top comprising a top frame, a strip of soft material on the top frame, a plate resting on said strip, said plate projecting beyond the sides 55 and ends of the top frame, a moulding surrounding the projecting edges of the plate and spaced from the top frame, and means for securing the moulding to the top frame in pressure contact with the edges of the 60 plate.

2. In counters and show cases, a top comprising a top frame, a strip of soft material on the top frame, a plate resting on said strip, said plate projecting beyond the sides 65 and ends of the top frame, a moulding sur-

rounding the projecting edges of the plate and spaced from the top frame, and means for securing the moulding to the top frame in pressure contact with the edges of the plate, said plate comprising two members 70 laid edge to edge with a space between, a yieldable gasket filling said space, said frame having a rest bar beneath the opposing plate edges.

3. In counters and show cases, a top comprising a top frame, a strip of soft material on the top frame, a plate resting on said strip, said plate projecting beyond the sides and ends of the top frame, a moulding surrounding the projecting edges of the plate 75 and spaced from the top frame, and means for securing the moulding to the top frame in pressure contact with the edges of the plate, said plate comprising two members laid edge to edge with a space between, a yieldable gasket filling said space and 80 cemented to the adjacent plate edges, said frame having a rest bar beneath the opposing plate edges.

4. A display top comprising a top frame, 90 a top plate laid on said frame, the area of which plate exceeds that of said frame, a moulding around the edges of said plate and spaced from said frame, and means for holding said moulding to said frame and in 95 pressure contact with the outer edges of said top plate.

5. A display top comprising a top frame, 100 a vitreous top plate laid on said frame, the area of which plate exceeds that of said frame, said plate comprising a transparent and an opaque section held edge to edge but spaced apart, and a rubber gasket filling the space between the opposing edges, a moulding around the edges of said plate and 105 spaced from said frame, and means for holding said moulding to said frame and in pressure contact with the outer edges of said top plate.

6. A display top comprising a top frame, 110 a vitreous top plate laid on said frame, the area of which plate exceeds that of said frame, a moulding around the edges of said plate and spaced from said frame, means for holding said moulding to said frame and in pressure contact with the outer edges of said top plate, and spacer washers located between said top frame and said moulding.

7. A display top comprising a top frame, 115 having outer flanges to fit over a cabinet on which it may be placed, a felt pad located on the top surface of said top frame, a top plate laid on said pad and extended beyond the outer edges of said top frame, a moulding 120 located around said top frame and spaced therefrom and adapted to be held in engagement with the outer edges of said top plate, and fastening devices for maintaining said moulding on said top frame and holding the 125

same in pressure contact with the edges of said top plate.

8. A display top comprising a top frame, having outer flanges to fit over a cabinet on which it may be placed, a felt pad located on the top surface of said top frame, a top plate laid on said pad and extended beyond the outer edges of said top frame, a moulding located around said top frame and spaced therefrom and adapted to be held in

engagement with the outer edges of said top plate, fastening devices for maintaining said moulding on said top frame and holding the same in pressure contact with the edges of said top plate, said fastening devices comprising screws passing through said moulding into said top frame, and spacer elements on said screws between said moulding and said top frame.

15

EDWARD FRIEDRICH.
